UNITED STATES PATENT OFFICE.

WILLIAM L. STEVENS, OF WOODSTOWN, AND MAURICE B. AYARS, OF SALEM,
NEW JERSEY; SAID STEVENS ASSIGNOR TO SAID AYARS.

CAN-FILLING MACHINE.

SPECIFICATION forming part of Letters Patent No. 417,686, dated December 17, 1889.

Application filed February 27, 1889. Serial No. 301,338. (No model.)

To all whom it may concern:

Be it known that we, WILLIAM L. STEVENS and MAURICE B. AYARS, citizens of the United States, residing, respectively, at Woodstown and Salem, in the county of Salem and State of New Jersey, have invented certain new and useful Improvements in Can-Filling Machines, of which the following is a specification, reference being had therein to the accompanying drawings.

Our invention relates to improvements in the patent granted to John Stevens, October 14, 1884, No. 306,658, for a can-filling machine; and the object of our invention is to, first, furnish a movement for actuating the cut-off or closing plate, which closes the end of the cylinder, so that this plate will only be lowered and the end of the cylinder open where the tomatoes or other materials are passing from the cylinder into the can, so that the can when filled may be immediately removed from the machine without any loss of time and without any of the material escaping; second, to furnish a face-plate which will have an annular projection upon it which will extend just inside of the mouth of the can, and which is furnished with perforations through which the air in the can will escape while the can is being filled; third, to furnish a yielding connection between the bifurcated actuating-lever and the plunger, which will insure uniformity in filling the can.

In the drawings, Figure 1 is a central sectional elevation of a can-filling machine embodying our improvements; Fig. 2, a side elevation of the same; Fig. 3, an end elevation of plunger and part of bifurcated lever, and Figs. 4 and 5 a front and side elevation of our face-plate.

As in the patent above referred to, A is a table or frame which carries a horizontal metallic bed C, in which rests a cylinder or tube B, which is drawn out or conical at its forward end, and which is furnished with a hopper b, in which the fruits, vegetables, or meats to be canned are placed.

H is a plunger, which forces the article into the can. This plunger is actuated, as described in the patent before referred to, by a bifurcated arm l, which is carried upon a

lever L, which is carried by a transverseshift E, journaled in suitable bearings in the frame A.

D is a shaft carrying a pinion m, which meshes into and drives a gear-wheel I, to the shaft G of which are also secured two cams g and g', the former of which, through lever K and connecting-rod F, actuates the lever L, and through arm l the piston H. For purposes of adjustment the upper end of rod F is furnished with a slot f, and the lever K is attached to arm F by a bolt f', passing through this slot. The other end of lever K is secured to arm l at k'.

The cut-off or closing plate p', which closes the end of cylinder B when the material is not being forced into the can, is operated as follows: i is a lever, one end of which is pivoted to the frame A at a, and the other end of which has pivoted to it one end of a link d, the other end of which is attached directly to the cut-off. The lever i rests upon the cam g', and during the revolutions of this cam the lever i is moved up and down, and through arm d moves cut-off p' up and down, opening and closing the end of cylinder B. The cam g' is so shaped and placed as to only lower the cut-off p' when the meats or vegetables are being forced into the can. Immediately after the can is filled the end of the cylinder is closed, the filled can withdrawn, and a new can put in place without danger of any of the materials escaping from the cylinder B.

The L-shaped lever J, which clamps the can in place while being filled, is actuated by a rod N, one end of which is secured to lever J, and which extends down and passes through lever L. n is a tappet on rod N. The rod N is bent over, as shown in the drawings, and to this bend is attached one end of a spring O, the other end being secured to lever L. After the can has been put in place the lever L moves down, drawing spring O down, and through rod N throws the lever J against the end of the can and holds the can in place. During the further downward movements of lever L the spring O gives, and hence the bottom of the can is not injured by the lever J exerting undue pressure upon it.

As the lever J rises it strikes tappet n on rod N and throws lever J away from and releases the can, which is then filled and ready to be removed.

- 5 In order that no material may escape while the can is being filled, we furnish the face-plate c', Figs. 4 and 5, with an annular projection e, which enters the hole in the top of the can. This projection e is furnished with 10 a number of holes f, through which the air in the can can escape while the materials with which it is being filled are being forced into it. These holes are not absolutely necessary, but are preferable.
- 15 In order to insure uniformity in filling the cans, we use a yielding connection between the arm l and the plunger H. Upon the plunger H is a cross-head P, Fig. 3. To this cross-head one end of the yielding connection is 20 attached, the other end being attached to the upper end of bifurcated arm l. The yielding connection consists of a spring h, Fig. 2, which is held in a frame k. One end of frame k is attached to cross-head P, and one end of the 25 spring h is secured to this frame by a screw

o. The other end of spring h is secured to arm l by a pin p. When the can is full and before the end of the stroke is reached, the spring h will give, and hence uniformity of filling is obtained without straining the can 30 or causing leakage between the can and face-plate.

Having thus described our invention, we claim as new and desire to secure by Letters Patent—

35 The combination, in a can-filling machine, of cylinder B, plunger H, arm l, with bifurcated top, cross-head P, frames k, springs h, cans g g', levers K and L, arm F, lever i, rod d, cut-off p', lever J, rod N, and spring O, all 40 arranged and operating substantially as and for the purposes set forth.

In testimony whereof we affix our signatures in the presence of two witnesses.

WILLIAM L. STEVENS.
MAURICE B. AYARS.
